UNITED STATES PATENT OFFICE

CHESTER A. BAKER, OF OMAHA, NEBRASKA, ASSIGNOR TO BAKER ICE MACHINE CO., INC., OF OMAHA, NEBRASKA, A CORPORATION OF NEBRASKA

REFRIGERATED CONTAINER

Application filed October 6, 1928. Serial No. 310,812.

My invention relates to refrigerating devices and more particularly to refrigerators adapted for employing ice for cooling purposes, the principal objects of the invention being to reduce the amount of ice necessary for retaining a cooled area at a desired low temperature, to isolate the ice from gases warmed by contact with material to be cooled, and to move air and odors from the cooled area.

Further objects are to promptly remove warm air leaking into the cooled area and to prevent warm air that may enter the cooled area from contacting the ice, and thereby prevent reduction in refrigerating efficiency by heat leakage.

Ice comprising a solidified gas such as carbon dioxide evaporating directly to a gas without a liquid phase, may be used as a refrigerating medium. Further objects of the invention therefore are to promote a circulation of gas from dry ice over material to be cooled, to cause the gas to move air and odors from the cooled area, and also to limit the rate of movement of the gas according to the amount of warm air leaking into the refrigerator whereby the refrigerant gas may be retained for maximum utilization in withdrawing heat from the material.

In accomplishing these and other objects of the invention, I have provided improved details of structure, the preferred forms of which are illustrated in the accompanying drawings, wherein:

Fig. 1 is a central vertical sectional view of a refrigerator embodying my invention, the lower ends of gas vent pipes and a food container being broken away to disclose structure.

Fig. 2 is a plan view from beneath of the bottom of a case-like lid and an ice support hinged to the lid.

Fig. 3 is a cross section of the refrigerator on the line 3—3, Fig. 1.

Fig. 4 is an enlarged vertical central sectional view of a valved gas outlet in the lid.

Referring in detail to the drawings:

1 designates an insulated housing including a vertical wall 2 and a bottom 3, of suitable shape, for example cylindrical, to receive ma-

terial that may be supported in a container 4 in spaced relation with the vertical wall, the container being preferably supported above the bottom by a spider-like bracket 5 and legs 6. A lid 7 closes the upper end of the housing, and includes a ring 8 overlying the upper edge of the housing wall.

The spacing of the container from the wall of the housing provides an annular cooling chamber divided into a plurality of channels 9 by partitions 10, which may serve as guides for positioning the container, and cool fluid may pass through the channels and be restrained therein in contact with the container to withdraw heat therefrom and retain the same at a relatively low temperature. The partitions preferably comprise conduits into which the fluid moves for passage away from the channels.

The invention is especially adapted for the use of dry ice such as solidified carbon dioxide and will be described as applied to such use.

An ice shelf 11 is mounted preferably above the upper end of the container and supported from the wall of the housing and is adapted for the passage of evaporating gas from the block of dry ice downwardly over the container. The conduits extend vertically in the channels 9, with their lower ends provided with openings 12 adjacent the bottom of the housing and their upper ends extending above the shelf, so that gas after passing downwardly over the container may move into the conduit to be conducted away from the housing.

When the gas is to be conducted upwardly through the conduits, the bottom of the housing is completely closed, and the conduits and lid are adapted for the movement of used gas out of the housing. The conduits have a total capacity much less than the capacity of the channels.

The lid 7 has a recess 13 in its lower side and the inner liner 14 thereof has an extended flange 15 adapted to overlie the inner vertical face of the upper end of the housing when the lid is positioned thereon, and the ice supporting shelf is preferably supported from the flange so that the block of ice 16 will extend in the recess.

The shelf preferably comprises a door or leaf having perforations 17 and hinged at 18 to an annulus 19 having its periphery attached to the flange and being provided with openings 20 for mounting the annulus over the upper ends of the conduits; the leaf filling the opening 21 of the annulus, whereby when the lid is removed, a block of ice may be inserted through the annulus opening and the leaf may be closed and latched by the latch 22 to support the block in the recess, when the lid is mounted on the housing.

An outlet opening 23 in the apex of the lid is provided with a valve 24 for controlled flow of gas from the housing. The outlet comprises a vertical tube 25 and a lateral branch 26, the valve 24 being a ball and being restrained by a cap 27 at the upper end of the tube.

In operating a refrigerator constructed in accordance with the illustrated application of the invention to the use of dry ice, the food to be cooled is installed in the housing, for example in the cylindrical container, and a block of solidified carbon dioxide is installed in the recess of the lid for support on the perforate leaf of the shelf. The lid is then mounted on the housing in sealing relation with the upper edges thereof so that the only outlet from the housing is through the valved opening in the lid.

The gas changing from solid to gaseous state moves downwardly through the apertures of the supporting shelf over the container and through the channels between the container and the housing to the bottom of the housing, absorbing heat from the container. The gas then passes through the openings in the lower ends of the conduits to move upwardly and into the lid, where it moves over the arcuate inner lining and out of contact with the block of ice toward the valved opening at the apex of the lid and so outwardly to atmosphere.

The downwardly moving column of cool gas hugs the surface of the container and also substantially fills the channels and moves air and warmed gas into the lower end openings of the conduits, thereby venting the air, warmed gas and odors together. Since the total cross sectional area of the conduits is materially less than the total cross sectional area of the channels, and the two elements are substantially the same length, balance is approached between the pressure of the downwardly moving streams of gas in the channels and the upwardly moving columns of slightly warmer gas in the tubes, tending to restrain the freshly evaporated gas in the channels and in contact with the container.

The warmer columns of gas rise into the upper area of the lid and relatively slight pressure therefrom tends to operate the outlet valve.

When the refrigerant has reduced the tem-

perature of the container substantially and the gaseous mixture in the upper ends of the conduits and upper area of the lid are at temperatures relatively close to the temperature of the freshly evaporated gas there will be relatively small movement outwardly from the housing and substantially only enough outward movement of vented gas will occur to permit freshly evaporated gas to move downwardly over the container.

The conduits receiving refrigerant gas that has passed over the container isolate the used gas from the container and from the freshly evaporated gas.

A further advantage of the withdrawal of the used gas from the channel and from contact with the container consists of the fact that any relatively warm air leaking into the housing is promptly removed from the channels and from the surface of the container and carried by the gas into the conduits. The warm air leakage is not only thus promptly removed from the cooling chambers but is restrained from contact with the refrigerant, since the vented products moving from the upper ends of the conduits pass along the surface of the top lining and do not come in contact with the block of ice.

The atmosphere of the refrigerated space is therefore constantly replaced by fresh, pure, cold, dry, carbon dioxide gas, which is quite harmless to products stored in it and is indeed considered to be an actual preservative of many foodstuffs. Any accumulation of odors in the stale air which would be confined within an ordinary refrigerator is avoided, and in addition the heat leaking through the wall is absorbed and vented along with the gas overflow. By venting the heat leakage in this manner, it is unnecessary for the refrigerant to absorb it and thus the amount of evaporation needed to keep a cold space cold is only that required to keep up a flow of gas through the vents large enough to carry the heat leakage with it, the gas passing out at a maximum temperature of the space. In other words, the incoming heat is carried out at the highest possible temperature, which may be decidedly higher (80° C. or more) than the temperature of the evaporating solid itself as contrasted with the case of water ice, for the liquid water leaving the refrigerator is at or near the temperature of the melting ice itself and hence must remove heat at the lowest feasible temperature differential, and in addition there is always the accumulation of undesirable odors in the necessarily confined air.

What I claim and desire to secure by Letters Patent is:

1. In a refrigerating device of the character described, a refrigerant-containing chamber, a container chamber located below the first named chamber and having vertical guides for spacing the container from the

5 chamber walls and forming vertical channels for gravity movement of refrigerant fluid through said channels, and means including a tube communicating with the lower end of the cooling chamber for passage of fluid from the channels.

10 2. A refrigerator comprising a housing adapted to contain food in spaced relation with the inner wall thereof, a hollow lid for sealingly closing the housing, means for supporting a refrigerating medium for downward movement of fluid from the medium between the food and the housing walls, and means including a tube extending in the 15 housing for conducting fluid from the housing.

20 3. In a refrigerator of the character described, a food-containing housing comprising a vertical wall having a plurality of vertical gas passages, means for supporting a gas-evolving refrigerating medium at the upper end of the housing for movement of refrigerating gas through the passages, and means communicating with selected passages 25 for conducting gas from the housing.

30 4. In a refrigerating device of the character described, a housing, a container in the housing, means spacing the container from the wall of the housing to form gas passages, means including a perforate plate for supporting a block of dry ice above the container for movement of evaporating gas downwardly in the passages, and means including a channel extending in said spacing means for 35 receiving gas from the lower portion of the passages for isolating said gas from the downwardly moving gas.

40 5. In a refrigerating device of the character described, including a housing adapted to receive a container spaced from the walls thereof, a hollow lid for the housing, having a valved outlet, a perforate plate hinged to the lid for supporting a block of dry ice above the container for movement of evaporating 45 gas downwardly over the container, and means including a tube extending between the container and the wall of the housing for conducting gas from the lower portion of the housing into the hollow lid for passage 50 through the valved outlet.

55 6. In a refrigerating device of the character described, a housing, a hollow lid for the housing having a valved gas outlet, a shelf hingedly engaged with the lid for supporting a block of dry ice, means for conducting gas evolved from said ice downwardly through said housing, and means communicating with said down conducting means and with the hollow lid for exhausting said gas 60 through the lid.

65 7. A container of the character described including an outer housing having a closed bottom, an inner container spaced from the side wall and bottom of the housing, forming an annular chamber and a bottom cham-

ber, means for supporting refrigerant at the top of the container, and open end tubes forming passages in the annular chamber and whereby gas evolved from the refrigerant is directed downwardly through said passages and upwardly through said tubes.

70 8. A container of the character described including an outer housing having a closed bottom, an inner container spaced from the side wall and bottom of the housing, forming an annular chamber and a bottom chamber, a dished lid for the top of the housing having an apertured floor forming a chamber for dry ice, tubes in spaced relation in said annular chamber open at their respective ends to said bottom chamber and to the chamber in said lid and forming passages in said annular chamber whereby gases evolved from ice in the ice chamber may pass down through said passages and return through 85 said tubes, and a valved gas outlet in said lid.

80 In testimony whereof I affix my signature.
